Attorney.

UNITED STATES PATENT OFFICE.

EMIL BÖSEBECK, OF BARMEN, GERMANY, ASSIGNOR TO MAX HENKELS, OF NEW YORK, N. Y.

MANUFACTURE OF LACE WITH BODY BEARING LEAFLIKE FIGURES.

Application filed September 7, 1923. Serial No. 661,536.

To all whom it may concern:

Be it known that I, EMIL BÖSEBECK, a citizen of the German Republic, and residing at Barmen, Rhenish Prussia, Germany, have invented certain new and useful Improvements in the Manufacture of Lace with Body Bearing Leaflike Figures, for which I have filed an application for patent in Germany on October 5, 1922, Serial Nr. H. 10 91,378 VII/25^b, and of which the following is a specification.

My invention relates to the production of braided lace on single-thread braiding machines. One of the objects of the invention 15 is to produce a braided lace which presents leaf-like figures or of figures of similar design firmly incorporated in the lace proper and extending laterally through the latter, by a novel method which renders the production more simple, rapid, and economical.

Heretofore, superposed leaf-like figures which are arranged with their major or longer axis in an angular position relatively 20 to the direction of length of the lace are produced in this way. A number of threads selected from the ground-work threads is conducted substantially in the longitudinal direction of the figure which, during its 25 formation is arranged with the longer axis parallelly with the direction of length of the lace, while simultaneously another selected thread is led to and fro in the transverse direction of the figure and thereby interlaced with the longitudinal threads, the weaving of the lace-ground or net being discontinued 30 during the time the figure is plaited. The leaflet so formed is then set at the desired angle, say at a right angle to the longitudinal 35 direction of the lace, whereupon the selected threads are again worked into the lace-ground and thus returned to the ground-work threads from which they had been taken. This mode of working is very 40 prosy; it requires much time and is, consequently, very expensive. Furthermore, the leaflets are connected to the lace-ground at 45 the two ends of each figure only, whereby the durability of the lace is greatly diminished. Finally, the figures are visible at one 50 side of the lace only, so that the application of the latter is limited to objects possessing merely one show-side.

Another object of my invention is to in-

crease the durability of such lace and at 55 the same time to produce figures of the kind referred to which appear to be superposed on both sides of the lace-ground.

With these and other objects in view my invention consists of a novel arrangement 60 and combination of threads based upon the principle described in my co-pending application Serial Nr. 611,065, filed January 6, 1923, according to which the selected threads which form the figure are interlaced not only with each other but also with those threads of the adjoining lace-ground which pass the place where a figure is to be formed. This principle is also applied to the manufacture of lace with body-bearing 65 figures arranged with their major axis in an angular position relatively to the direction of length of the lace, with the modification, however, that a number of threads selected from the ground-work threads are 70 conducted to and fro in the longitudinal direction of the figure and interlaced only with a plurality of ground-work threads 75 which are led transversely through the leaflet, the latter being thereby from the beginning positioned at the desired angle to the longitudinal direction of the lace.

By these means the production of lace with leaf-like figures arranged with their major axis at an angle to the direction of length of the lace is materially simplified. The weaving of the lace-ground need no more be discontinued during the formation 80 of the leaflets, on the contrary, those parts of the lace-ground or net and of the lace edge which, looked at in the direction of breadth of the lace, are disposed at both sides of a figure can be braided simultaneously with the latter. Consequently, the time necessary for manufacturing a given length 85 of lace is shortened. Furthermore, the leaf-like figures are now at every place of their entire length connected to the lace-ground, and finally, they appear to be superposed on 90 the front as well as on the back side of the lace.

The new process of making superposed leaf-like figures of the kind above referred to is more fully explained in the following 105 description, reference being made to the annexed drawing which shows, by way of example, a preferred embodiment of the new lace.

In the drawing,

Fig. 1 is a piece of lace of about actual size,

Fig. 2 is a part of that lace drawn on an enlarged scale and showing the novel arrangement and combination of threads in a leaf-like figure.

The lace shown is a so-called "torchon" lace comprising groups of four leaf-like figures arranged in the form of a so-called Maltese-cross. My invention may, however, also be applied to lace of any other kind.

Referring first to Fig. 1, the lace comprises a wide-meshed net consisting of two groups of diagonally arranged braided bars *a*, *a* interconnected at their respective crossing points. At certain places, the wide-meshed net is, as usual in "torchon" lace, replaced by a small-meshed net *b* which is formed by unravelling the braided bars *a*, *a* into single threads or strands and leading the latter partly in the diagonal, partly in the transverse direction of the fabric, thereby interlacing them in a manner known as "half-stitch."

To each part *b* of the lace-net a group of four body-bearing leaflets *c*, *c*¹, *d*, *d*¹ arranged in the form of a so-called Maltese-cross is applied. The longer axis of the leaflets *c*, *c*¹ are parallel with the longitudinal direction, i. e. the direction of length of the lace, whereas the leaflets *d*, *d*¹ are arranged with their longer or major axis at a right angle to said direction.

The leaflets *c*, *c*¹ are produced in the manner described in my co-pending application Serial Nr. 611,065, that is to say, they consist of a number of selected threads running substantially in the longitudinal direction of the figure and of another selected thread led to and fro in the transverse direction of the figure and interlaced with the said longitudinal threads as well as with a plurality of threads of the adjoining lace-net which are conducted transversally through the figure. The leaflets *d*, *d*¹ are formed in a similar manner by means of one or more selected threads running to and fro and a number of ground-work threads led transversally through the figure. However, the formation of the leaflets *d*, *d*¹ differs from that of the leaflets *c*, *c*¹ in the facts that, on the one hand, merely ground-work threads *m*, *m*, i. e. threads of the adjoining lace-net are conducted transversally through the figure, while, on the other hand, the selected threads *n*, *o* are led to and fro in the longitudinal direction of the figure, said selected threads being, at the same time, interlaced with said ground-work threads *m*, *m*, as more fully shown in Fig. 2. In order to obtain the desired pointed ends of the leaflet, the threads *n*, *o* run in the middle of the figure over the entire length of the latter, while at the side parts of the leaflet said

threads *n*, *o* are conducted over parts of the length of the figure only, that is to say, the closer the convolutions of the threads *n*, *o* are to the ends of the minor axis of the figure the shorter are the convolutions, and the smaller is the number of threads *m*, *m* interlaced with the threads *n*, *o*. The edges of the leaflet are, preferably, formed by threads *p*, *p*, *q*, which frame the figure formed by the threads *n*, *o* and *m*, *m*. These threads *p*, *p*, *q* may at the returning places of the threads *n*, *o* be embraced by the latter in a similar manner as in my co-pending application the longitudinal threads *f*, *f* are embraced by the thread *g*.

The selected threads *n*, *o* may be thicker than the other threads of the lace. When four leaflets are arranged in the form of a cross, as shown, I prefer to produce a longitudinally arranged leaflet *c* or *c*¹ and a transversely arranged leaflet *d* or *d*¹ by means of one and the same selected thread. For instance, that thread which was led to and fro in the figure *c*¹ is conducted into the leaflet *d*¹, and then led to and fro in this figure. When, however, on looking at the lace in the direction of breadth, parts of the leaflets *c*¹ and *d*¹ are disposed side by side, the selected thread taken from the longitudinal leaflet *c*¹, and this is the thread *n* in Fig. 2, can only work part of the figure *d*¹, the rest of the latter being formed by another selected thread, the thread *o* in Fig.

2. In the leaflets *c*, *d* the arrangement of the threads is similar, the only difference being this that the selected thread which commonly forms the figure *c* and part of the figure *d* is first led to and fro in the leaflet *d* and then conducted into the figure *c*, because the figure *d* is, looked at in the working direction of the lace, positioned before the leaflet *c*.

I wish it to be stated that my invention is not limited to the exact lace shown and described for many alterations and variations may suggest themselves to those skilled in the art without departing from the scope of my invention as pointed out in the claims. Especially, the invention is not restricted to the application of the figures to a lace-net worked in a so-called half-stitch, on the contrary, the leaf-like figures produced according to my invention may also be applied to any other known lace-net. Finally, the number of selected threads used for forming a figure may be altered, if desired.

Claims:—

1. The method of producing machine-braided torchon lace with leaflets standing out in relief from both sides, the major axis of which leaflets extends transversely of the major axis of the lace, which method comprises forming each leaflet by leading a plurality of ground threads in warplike interspaced manner transversely to the

major axis of the leaflet and by then leading at least one selected ground thread in close weftlike interlacing manner to and fro through said warp threads and finally returning said selected thread back to the ground again.

2. The method of producing machine-braided torchon lace with leaflets standing out in relief from both sides, the major axis of which leaflets extends transversely of the major axis of the lace, which method comprises forming each leaflet by leading a plurality of ground threads in warplike interspaced manner transversely to the major axis of the leaflet, and by then leading other selected ground threads in closely aggregated loops in weftlike intercrossing manner to and fro through said warp threads, the loops of said selected threads diminishing in extent toward the sides of the leaflet and thus engaging a correspondingly decreasing number of said warp threads.

3. In the method according to claim 2, the step of using still other ground threads for framing the leaflet by interlacing them with one another and with the weft and the warp threads as they emerge from the leaflet.

4. Machine-braided torchon lace with leaflets standing out in relief from both sides, the major axis of which leaflets extends transversely of the major axis of the lace, each leaflet being formed by spaced

ground threads extending in warplike manner transversely through the leaflet, and by at least one selected ground thread interlacingly led in weftlike manner to and fro through said warp threads in closely aggregated loops in the longitudinal direction of the leaflet.

5. Machine-braided torchon lace with leaflets standing out in relief from both sides, the major axis of which leaflets extends transversely of the major axis of the lace, each leaflet being formed by interspaced ground threads extending in warplike manner transversely through the leaflet, and by selected ground threads interengagingly led to and fro in weftlike manner through said warp threads in closely aggregated loops in the longitudinal direction of the leaflet, and the longitudinal extent of these loops diminishing toward the sides of the leaflet and correspondingly interlacing in the central part of the leaflet all of said warp threads and a gradually decreasing number thereof toward the sides of the leaflet.

6. In a machine-braided torchon lace according to claim 5, the feature that each leaflet is framed by other ground threads interlaced with one another and with said warp and weft threads on their emergence from the leaflet.

In testimony whereof, I affix my signature.

EMIL BÖSEBECK.
